US0D1063850S

(12) **United States Design Patent** (10) **Patent No.:** **US D1,063,850 S**
(45) **Date of Patent:** **** Feb. 25, 2025**

(54) **COMBINED ADAPTER AND CONNECTOR FOR ELECTRICAL STIMULATOR**

- (71) Applicant: **SPR Therapeutics, Inc.**, Cleveland, OH (US)
- (72) Inventors: **Matthew G. deBock**, Morrisville, NC (US); **Joseph W. Boggs, II**, Chapel Hill, NC (US); **Matthew J. Wunzin**, Cleveland, OH (US); **Robert B. Strother, Jr.**, Willoughby Hills, OH (US); **Devin Sell**, Brecksville, OH (US); **Mark R. Stultz**, Maple Grove, MN (US); **Bradley A. Lewis**, Lyndhurst, OH (US)
- (73) Assignee: **SPR Therapeutics, Inc.**, Cleveland, OH (US)
- (**) Term: **15 Years**
- (21) Appl. No.: **29/851,121**
- (22) Filed: **Aug. 25, 2022**

(57) **CLAIM**

The ornamental design for a combined adapter and connector for electrical stimulator as shown and described.

DESCRIPTION

FIG. 1 is a top perspective view of combined adapter and connector for electrical stimulator showing our new design; FIG. 2 is a bottom perspective view thereof; FIG. 3 is a top view thereof; FIG. 4 is a bottom view thereof; FIG. 5 is a first side view thereof; FIG. 6 is a second side view thereof; FIG. 7 is a front view thereof; and, FIG. 8 is a rear view thereof.
The broken lines in the drawings are for the purpose of illustrating portions of the article that form no part of the claimed design.

1 Claim, 7 Drawing Sheets
